(57) **CLAIM**

The ornamental design for a bed, as shown and described.

DESCRIPTION

FIG. 1 is a front left perspective view of a bed showing our new design;

FIG. 2 is a front elevation view thereof;

FIG. 3 is a right side elevation view thereof, the left side being a mirror image;

FIG. 4 is a top plan view thereof;

FIG. 5 is a front left perspective view of a second embodiment of a bed showing our new design;

FIG. 6 is a front elevation view thereof;

FIG. 7 is a right side elevation view thereof, the left side being a mirror image;

FIG. 8 is a top plan view thereof;

FIG. 9 is a front left perspective view of a third embodiment of a bed showing our new design;

FIG. 10 is a front elevation view thereof;

FIG. 11 is a right side elevation view thereof, the left side being a mirror image; and,

FIG. 12 is a top plan view thereof.

The broken lines show environmental subject matter and form no part of the claimed designs. The beds of the embodiments of FIGS. 5-12 are shown with symbolic breaks in width. The appearance of any portions of the beds between the break lines form no part of the claimed designs.

1 Claim, 12 Drawing Sheets
